UNITED STATES PATENT OFFICE

2,077,837

PROCESS FOR THE REFINING OF SPERM OIL
OR WAX

Wilhelm Holwech, Oslo, Norway

No Drawing. Application February 4, 1935,
Serial No. 4,993

2 Claims. (Cl. 202—52)

This invention relates to marine oil products of the type containing a high percentage of esters of wax alcohols and has for its object a process of improving the quality of this type of material.

It is known that a group of animal oils obtained from dentice whale, delphines and certain classes of shark contain a high percentage of unsaponifiable matter substantially consisting of monovalent alcohols of high molecular weight, present in the oil in the form of fatty acid esters. These esters possess the character of solid and liquid waxes.

In addition to esters of wax alcohols the commercial oils of this type frequently also contain a percentage of glyceride fats. In most of the uses to which the oils are put, this percentage of glycerides is however undesirable and is considered as a harmful impurity. As a consequence of this the commercial value of the oils decreases with increasing percentage of glycerides and it therefore represents a problem of considerable industrial importance to separate the glycerides from the esters of the wax alcohols.

The solution of this problem, however, is connected with great difficulties, and as far as I am aware of the various attempts hitherto made to solve this problem have not met with success.

To remove the glycerides by means of saponification is not possible because the esters of the wax alcohols are saponified simultaneously with the glycerides. Attempts to effect separation by means of fat-decomposing ferment have also not led to practically useful results.

The present invention now has for its object a process by means of which a sufficiently complete separation of the glycerides from the said esters of alcohols other than glycerol is obtainable. This invention is based on the surprising discovery that the esters of the wax alcohols contained in the said oil are capable of being distilled off from the glycerides without being decomposed to any appreciable degree.

An important feature of the present process therefore consists in subjecting the products in question to a distillation treatment. The use of distillation under reduced pressure to separate free fatty acids from glycerol esters is well known. And it is also well known to refine fatty acids by means of such distillation. The fatty acids are known to be volatile in vacuum at temperatures from about 150° C. to about 280° C., but the esters have been considered as nonvolatile. Thus according to the present knowledge the glycerol esters of fatty acids having molecular weights

above that of myristic acid cannot be distilled without decomposition even by the use of the highest vacuum attainable by modern means.

Contrary to the generally recognized conceptions regarding the stability of fatty acid esters of high molecular weight at high temperatures it has now been ascertained that the wax-like esters of the marine oils in question are capable of being separated from the glycerol esters by distillation.

The process according to the invention is applicable to the oils as well as to products of semi-liquid or solid consistency obtained from the oils and in general to any product containing mixtures of fatty acid glycerides and wax-like esters of the type contained in sperm oil.

The temperatures and pressures employed in the distillation will have to be varied between wide limits according to the character of the oil as well as to the purpose for which the products are to be employed. Products sensible to heat should be distilled at comparatively low pressures, while less sensible oils or waxes may be subjected to comparatively high distillation temperatures. By means of fractional distillation the various constituents of the distillable matter may be recovered separately.

The completeness of the separation of glycerides from other esters will vary with the character of the material and the conditions of operation. The same remark applies also as regards the percentage of the waxy esters present which are distilled off from the treated material. As an example may be mentioned that in one of the experiments made the distillate obtained from a sperm oil containing about 15 percent of glycerol esters and about 85 percent of waxlike esters, about 85 percent of the total quantity of waxlike esters were distilled over a temperature of up to about 340° C.

The composition of the distillation residuum will vary with the distillation temperature and other conditions and will comprise varying percentages of waxlike esters, glycerol esters and decomposition products. Usually it will be practically free from acids.

When sufficiently high temperatures have been employed the distillate will contain the solid as well as the liquid waxlike esters of the raw material. The surprising observation is made that the percentage of free fatty acids in the distillate is low and usually only slightly higher than in the raw material, in spite of the fact that very high distillation temperatures are made use of. In some of the experiments made it has been

found that the percentage of free fatty acids increased from about 0.25 per cent to about 1.55 per cent.

During the distillation operation indifferent gases or steam in a superheated or moist condition or any other vapour for example vaporized organic substances may be passed through the distillation chamber when desired.

It may also sometimes be suitable to make use of the method known from the fatty acid industry, consisting in mixing the original oil with other substances having a lower boiling temperature, for example; benzene, benzine, petroleum, alcohols and the like and to subject the mixture to the distillation treatment. The added volatile substances will evaporate and will bring about a decrease of the partial pressure of the waxlike esters in the vapour, so that the distillation may take place at a correspondingly lower temperature. It is possible to so elect the volatile substances added that they are capable of being readily separated from the distilled esters by fractional condensation or other fractionating treatment.

25 The distillation operation may be carried out as a simple vacuum distillation in batch operation or it may be carried into effect as a fractional distillation in continuously operated apparatus.

EXAMPLE 1

Vacuum distillation in batch operation

35 Sperm oil containing 0,25 per cent free fatty acids, about 15 per cent glyceride fat and about 85 per cent wax-like esters was heated in the distillation apparatus, an inert gas (nitrogen) being blown into the oil. During the distillation the pressure was maintained at about 5-10 mm. Hg. The following fractions were obtained:

	Percent of the oil
Fraction 1. 20° to 305° C.	14
Fraction 2. 305° to 325° C.	43
Fraction 3. 325° to 340° C.	14
Distillation residuum	28

45 Fraction 1, contains free fatty acids originated from the original oil. In Fraction 2, only very little free fatty acids are contained, while Fraction 3, again contains free fatty acids derived from a beginning decomposition.

50 The distillation residuum is practically free from acids. All of the fractions are capable of being freed from free fatty acids by means of a treatment with alkali or by means of a fractional distillation.

EXAMPLE II

Continuous distillation in column apparatus

A marine oil containing wax-like esters is heated in a system of pipes to the desired temperature (for example 340° C.). The heated oil is passed into a column apparatus of the usual type employed in the vacuum distillation of fatty acids. Temperature of feed and amount of reflux is controlled in such way that about 20-30% of the oil containing the main part of the not distillable glyceride fat is taken out at the bottom of the column.

The vapours from this first stage of the process are passed into another section of the same or into another column and are subjected to fractional condensation. 65 to 75 per cent of the oil containing the main quantity of wax-like esters are present in the vapours and may be condensed.

The temperature in the upper part of this column can be maintained at such height that the main quantity of the free fatty acids is still present in the form of vapour. This temperature will vary with the pressure employed and the character of the fatty acids present and may for example be presumed to be about 180° C. to 280° C. The vapour from this stage is passed to the condensation apparatus and to the pump by means of which the required vacuum is maintained.

EXAMPLE III

Sperm oil is subjected to the treatment usually employed to separate spermwax from the oil. The crude wax is subjected to distillation according to Examples I or II. The remaining oil is separately distilled according to Examples I or II. The residuum from the distillation of the wax is mixed with the residuum from the oil distillation and is employed as a raw material in the manufacture of soap. 15 20

EXAMPLE IV

Distilled wax-like esters obtained according to Examples I, II, or III are cooled to effect crystallization of the solid fraction of the material. The solids are removed by pressing and both fractions freed from fatty acids. The resulting products are suitable for every use in which a sperm oil or a sperm wax of high grade quality is required.

EXAMPLE V

Distilled wax-like esters obtained according to Examples I, II, or III are subjected to a hardening treatment by means of hydrogen in the presence of a catalyst. 32

The hardening may be arranged as a treatment of the liquid fraction freed from the solid fraction by cooling and pressing.

The resulting wax is suitable for every use in which a wax of high grade quality is required. 40

It will be understood that the invention is not limited to the various details of operation mentioned in the above examples and that the raw materials employed as well as the conditions of operation may be varied within wide limits.

The products obtained by the distillation treatment are suitable for direct use in the various field in which sperm oil and wax is commonly employed, such as for example as lubricants, candles, dressing means, soap manufactures, cosmetics, ointments etc. 50

The products may also be subjected to further refining treatments and as a raw material in various industries in which the products are decomposed or converted into chemical products for uses other than those of crude or refined oils or waxes. 55

It is possible by cold clarifying and pressing of the distillates to separate out liquid wax-like esters solidifying at low temperatures. Such cold clarifying products which are practically free from glyceride fats possess excellent properties as a lubricant for machinery and instruments. They may be used as such or in mixtures with mineral oils. In the last named instance, that is to say, in the manufacture of socalled compounded oils the advantage is attained that an increase of compounding agents does not involve an increase of the percentage of glyceride fat. It is a known fact that compounded oils are of limited usefulness because in many instances the glyceride fat is a harmful constituent. The cold-clarifying products are of great advantage as a constituent of drilling oils, textile oils, cosmetic preparations and generally for all

purposes in which cold-clarified sperm oils have hitherto been used.

From the press residuum after separation of the liquid fraction wax esters of high melting 5 points may be produced.

These wax-like products are suitable for use in all of the fields in which sperm wax has hitherto been used. These products are particularly advantageous because they are free from 10 glyceride fat.

As will be understood from the above, various products obtained by the vacuum distillation according to the present invention are capable of being converted into valuable products by catalytic hydrogenation processes. The advantage 15 of such further treatment will be apparent from the following.

From marine oils or oil products of the type containing wax-like esters it is possible by fractional distillation to obtain distillates practically 20 free from glyceride fat (less than 1 per cent).

It may be mentioned that in a particular example distillation products containing 40.2%—46.4%—48.4%—51.3% unsaponifiable alcohols, 25 62.8%—57.4%—56.5%—52.3% saponifiable fatty acids, having iodine numbers of 76.0—83.7—85.0—100.0 and being practically free from glyceride fats have been obtained by fractional distillation of a sperm oil containing 14.5% glyceride fat, 32.4% unsaponifiable alcohols, 65.9% 30 saponifiable fatty acids and having an iodine number of 86.

By catalytic hydrogenation of the products, wax-like esters having high melting points and 35 low iodine numbers may be obtained and which in composition are very much like the best known qualities of refined sperm wax qualities.

These last named types of wax according to the literature have a composition as follows: 40 41%—54.3% unsaponifiable alcohols, 49—53.5% saponifiable fatty acids, iodine numbers 3—8 and glyceride fats up to about 7%. The hardened distillation products according to the present invention will thus be of a quality superior to refined sperm waxes because they do not contain 45 glyceride fat.

By direct hydrogenation of undistilled sperm oil, products are obtained which contain 30—40 per cent unsaponifiable alcohols, 60—68 per cent 50 saponifiable fatty acids and 10 to 18 per cent of glyceride fat.

Even by the most extensive hydrogenation of undistilled sperm oil it is not possible to produce products of a composition corresponding to that 55 of sperm wax of ordinary quality. The difference in composition, particularly the percentage of glyceride fat, will have a harmful influence on the quality.

The hydrogenation treatment may be applied 60 to each individual fraction of the distillate and

also to the distillation residuum. The hydrogenation may be carried out as a separate operation, in which the various fractions (or the residuum respectively) are treated. It may, however, also be carried out as steps of the distillation itself or in immediate conjunction therewith. The distillates are capable of being hydrogenated in liquid conditions as well as in the form of vapours.

In certain cases it is found to be of advantage to elect hydrogen as the gas which is blown into the still to facilitate distillation. Hydrogen has a low molecular weight and will therefore increase the rate of diffusion of the ester vapours. The use of hydrogen will be of special importance in case the distillation is carried out in combination with a hydrogenation treatment.

In the case of the hydrogenation being carried out in combination with the distillation and while the distillates are still in the form of vapours the hydrogen pressure will have to be lower than atmospheric pressure. In the case of the distillates being hydrogenated in a liquid condition the hydrogen pressure may be raised above atmospheric pressure, the known methods of high pressure hydrogenation of unsaturated organic substances being then applicable.

This high pressure hydrogenation may also be applied to the distillation residuum which consists of a mixture of glycerol esters and unsaponifiable matter. In one of my experiments the obtained residuum contained 10 per cent of unsaponifiable alcohols and 85 per cent of saponifiable fatty acids.

By hydrogenation at high pressures according to known methods of procedure the fatty acids in the residuum are converted into alcohols of corresponding molecular weights (thus 40 raising the contents of alcohols from 10 per cent—in the example mentioned—to a percentage which makes the manufacture of pure wax alcohols possible).

I claim:

1. Process for the refining of such materials of the sperm oil type, which contain in addition to the natural wax-like esters also a notable amount of glycerol fat comprising the step of subjecting the material to distillation under reduced pressure at temperatures sufficiently high to effect evaporation of the natural wax-like esters in an unsplit condition leaving the glycerol fat as a residuum.

2. Process according to claim 1 in which the distillation is effected at temperatures up to about 340° C. at pressures at about 5—10 mm. Hg.

WILHELM HOLWECH.
